Patented Feb. 16, 1915.

2 SHEETS-SHEET 2.

UNITED STATES PATENT OFFICE.

KARL MAIER, OF STUTTGART, GERMANY, ASSIGNOR TO THE FIRM OF UNION SPEZIAL-MASCHINENFABRIK G. M. B. H., OF STUTTGART, GERMANY.

INDICATOR MECHANISM FOR COIN-ISSUING APPARATUS.

1,128,888.

Specification of Letters Patent. Patented Feb. 16, 1915.

Application filed July 13, 1908. Serial No. 443,228.

To all whom it may concern:

Be it known that I, KARL MAIER, a citizen of the German Empire, residing at Stuttgart, in the Kingdom of Wurttemberg, Empire of Germany, have invented certain new and useful Improvements in Indicator Mechanism for Coin-Issuing Apparatus; and I do hereby declare the following to be a full, clear, and exact description of the invention, such as will enable others skilled in the art to which it appertains to make and use the same.

This invention relates to a novel adjusting device for the indicating mechanism for coin-issuing apparatus. In it two number segments each are employed for the dollars and cents, which at the same time on the paying out of an amount by depression of one key for dollars and one key for cents, are so operated that any figure with two numbers consisting of tens and units may be simultaneously indicated and put together and the sum in question revealed. For this purpose, revoluble frames are arranged connected with the number segments in such manner that their rotation or adjustment depends upon the magnitude of the oscillation of the frames. In order to obtain different oscillations of the frames corresponding to the different number values, the frames are provided with step-like ledges adapted to be struck by the rail pieces of the keys, this striking of the rail pieces upon the steps taking place sooner or later, corresponding to the number value of the key pressed.

One object of my invention is to do away with the necessity of turning the number segments back to zero after each indication and before a new indication can be made.

The improvement extends to an essential simplification of the adjustment device and its manipulation, whereby a complete security of operation, especially with regard to the exactness of the adjustment is realized. For this purpose, a returning of the number segments back into the zero position is done away with, as the same can be turned from every adjustment by means of the device at once into the new position. According to the preceding position, a forward or backward turning of the number segments is now required in this connection. This is attained by the present invention through the employment of a pair of

frames, provided with steps corresponding to the different number values, the frames of which are positively connected in such manner that the one frame moves oppositely and turns the number wheels backward, while the latter are turned forward by the other frame. This drive renders possible at the same time a stopping of the moved parts in the position corresponding to the value of the number, in such manner that an over- rotation over the mark of the number wheels is excluded.

The object of the present invention is elucidated on the drawings through an embodiment by way of an example.

In the accompanying drawings, Figure 1 is a front view of my invention. Fig. 2 is a side view. Fig. 3 is a plan view. Figs. 4 and 5 are details showing how the number segments are locked. Fig. 6 is a vertical transverse sectional view of an apparatus embodying my invention.

Referring now to the drawings, 1 represents the case of the improved cash register and change-maker, which is provided with the key-boards 2 and 2', the board 2 representing the dollars, and the board 2' the cents Fig. 1. The keys 100 in number in each set are guided in the fixed plates 4 and 4' carried by the case 1, and provided with rods 3, and surrounding said rods are springs 6, which normally hold the keys 2 in their raised positions, as clearly shown in Figs. 2 and 10.

The bars 3 are each provided with a key rail 7, which vary in length for every key for the dollars and cents or are formed in such a manner that each rail 7 consists virtually of several joined pieces, as clearly shown in Fig. 10 of the drawings.

Arranged with the case below the key rails 7, is a series of levers 8 forming cranks, Fig. 6 each of which turns on a pivot 9 and is connected by a bolt 10 to the link 11. The end of said link is connected with a lever 12 for operating the ejectors, it being understood that there is one of these levers 12 for each ejector.

It will be understood that the coins are fed forward as they are ejected in any suitable way, and are discharged at the front end of the machine through a channel into a receptacle placed below the same.

As heretofore stated, a number of ejectors are provided, and for each ejector a recep-

tacle 16 is provided, in which the coins 15 are stacked.

Within the receptacle is a carriage 18, secured to a spring 20, the end of which is secured at 21 to the receptacle 16, and the spring is wound around the drum 19, whereby the coins are fed forward as they are ejected.

The coins as they are ejected from the carriage, drop into a coin channel 17, and are discharged at the front of the machine into the desired receptacle placed below the lower end of the channel.

As heretofore stated, according to the invention, an adjusting device for the indicating mechanism is provided, which consists essentially of steplike frames operated by the keys, and so arranged and constructed that they are rocked more or less according to the value of the depressed key, and said frame is connected to the number wheels.

The key rails 7 have extensions 22, clearly shown in Figs. 2, 4, and 6, which engage the stepped edges of the frame pair 23, 24, and the frame pair 25, 26, the pair of frames 23, 24, adjusting the units and the pair of frames 25 and 26 adjusting the tens. The frame pairs 23, 25, have respectively stepped ledges 27 and 28, which are engaged by the extension 22 of the key rail 7. On striking a key of a high number, the projection 22 will engage one of the upper steps 27 or 28, and on striking a key of a lower number, the projection engages one of the lower steps and thus the indicating means is moved more or less, so that the amount indicated is varied, as will be hereinafter more fully described.

40 The frame pairs 23 and 25 are loosely mounted on a shaft 29 in the case 1 of the register. The said frames are provided with rigid levers on the opposite side of the shaft 29, and said levers are connected to links 31. Said links are in turn connected to segments 32, pivoted at 49. The said segments are provided with teeth which mesh with cog wheels 33 carrying the number wheels 34 and 35. One of the levers 30 is, therefore, connected with the tens frame 25, and the other with the units frame in such a manner that they can rotate independently of each other.

55 In order to avoid the returning of the figure wheels 34 and 35 to zero, after each registering operation, and also to avoid separate stopping devices, I provide two tens frames 25 and 26, and two units frames 23 and 24 of the same kind, but in this connection the steps 36 and 37 of the added frames 24 and 26 extend in opposite directions, as clearly shown in Figs. 2, 3, 4 and 5 of the drawings. These frames 24 and 26 are likewise loosely mounted upon the shaft 29, and connected with the frames 23 and

25 in such a manner that the two tens frames 25 and 26, as well as the two units frames 23 and 24, work against each other, so that the movement of one in one direction moves the other in the reverse direction, and when the two engage the projection 22 of the key rail, the movement is limited, and the proper amount designated by the key depressed, is registered. For this purpose, the frames 23 and 24 are in connection at both ends with each other, through levers 38 and links 39, with an elbow lever 40 rocking around the shaft 41. The opposite end of the bell crank lever 40 is connected through a link 42 with a lever 43 rigidly secured to the frames 25 and 26. By this arrangement, it will be seen that the working of either of the frames in one direction, moves the other frame in the opposite direction until both frames are stopped by the engagement thereof with the projection 22 of the key rails. It will be understood that the operation of the cents and dollar keys and frames are exactly alike.

The operation of the machine is as follows: A key 2 is depressed and the extension carried by the key rail 7 comes in contact with the step corresponding to the figure value of one of the units frames and one of the tens frames, and starts them into rotation. If for instance, the frame 26 is moved out of the position shown in Fig. 4 in the direction of the arrow, owing to the link connection between the same and the frame 25, the said frame moves in the opposite direction. This contrary movement of the frames and depression of the keys can only take place so long until the corresponding cooperating steps 28 and 36 of the two frames 25 and 26 meet, that is, until the correct adjustment of the figure wheels 34 or 35 is completed, in which case the extension 22 lies upon both steps of the frames (Fig. 6) the one of which (36) is pushed upward by the extension 22, while the other one (28) is hereby simultaneously moved downward. In this manner, the extension 22 comes in contact with the two steps 28 and 36, and a further turning of the figure wheels 34, 35 is excluded. If, for instance, a dollar key is pushed and another dollar key is then pushed, a turning of the frames in the one or the other direction takes place, according as by the new adjustment a higher or lower value of figures than before is pushed. The machine is thus in a position having indicated a certain amount, and upon releasing the key, the same returns to its normal position, but the frames and the indicating device remain in the indicated or stopped position, as heretofore stated. Another key being depressed, the projection 22 engages another notch, which might be higher or lower, and moves the frames in opposite directions, until the

corresponding notches engage the projection 22, which either moves the indicating wheels forward or backward, and indicates the amount of the key last depressed.

5 The above described device is now duplicated, one for the dollar keys and one for the cents keys, and to each arrangement belong one each of units figure wheels and one of the tens figure wheels, whereby the 10 wheels are doubly arranged and connected among themselves.

Further type wheels 48 are provided, which are mounted upon shaft 49 and sleeves 50. The shaft 49 carries the segments 32, 15 so that the rotation of the same rotates the sleeve 50 and shaft 49, and the type wheel 48.

In Figs. 1 and 2, the frame pairs 23, 24 and 25, 26 are to be recognized, with their extensions 22 upon the frames, and the influence of the key-rail 7 upon the cranks 8. 20 Actually 99 key-rails 7 lie side by side or contiguously, although but a small number of the key-rails 7 is represented, as otherwise the steps of the stairslike frame would be hidden. In practice as many cranks 8 are required as there are ejectors 14.

Having fully described my invention, what I claim as new and desire to secure by Letters Patent, is:—

20 1. In a device of the character described, number segments, a plurality of keys, prolongations on the respective keys, a series of pairs of frames provided for numbers, which consist of tens and units, which 25 frames are in connection with the number segments and are provided with stepped projections corresponding to the number values, on which stepped projections the prolongations of the keys strike and cause 30 the pairs of frames to turn, each according to the number value whereby a number composed of tens and units may be put together simultaneously with one key and the sum in 35 question indicated.

40 45 2. In a device of the character described, comprising number segments, a plurality of key bars, two co-acting frames (23, 24 and 25, 26) stepped in opposite directions and adapted to move in opposition to each other 50 and cooperate with the segments to move against one another so that the steps on meeting form a stop for the key bars, one frame (23 or 25) operating the forward movement of the number segments, and the 55 other (24 or 26) its return movement.

3. In a device of the character described comprising the frames 23, 24 and 25, 26, arranged in pairs and adapted to move in opposition to each other, segments and co-operative means between the segments and the frames to display on the convex surface of the segments the amount indicated by the frames.

4. A device of the character described, 60 comprising indicating segments, means for

operating said segments, and means for operating said segments without first returning to zero, said means comprising keys, pairs of pivotal frames oppositely stepped, and means for rotating them in opposite 70 directions.

5. In a device of the character described, the frames 23, 24 and 25, 26 arranged in pairs, levers and links connecting the same, whereby they are necessarily operated in opposite directions, number segments, and co-operative means between the number segments and the frames to display on the convex surface of the segments an amount corresponding to the movement of the 80 frames.

6. In a device of the character described, the co-acting frames 23, 24 and 25, 26 oppositely stepped, four number segments, 85 said frames moving in opposition to each other and co-operating with the segments to move against one another, whereby the steps at their meeting point form a stop for the key bar, one of said frames regulating the forward movement of a number segment 90 and the other its return movement.

7. A device of the character described, comprising indicating segments, keys, frames connected to the segments and arranged in pairs and the frames of each pair 95 connected, to be moved in the opposite direction to the other by the movement of either frame, and means carried by the keys for operating said frames.

8. A device of the character described, 100 comprising indicating segments, frames connected to the segments and arranged in pairs and the frames of each pair connected, to be moved in the opposite direction to the other by the movement of either frame, and 105 keys having means for engaging one frame of a pair and moving it until both frames engage the keys, when the device is locked and the amount designated by the operated key is indicated. 110

9. A device of the character described, comprising indicating segments, stepped frames connected to the segments and arranged in pairs, the step of the frames of the pairs arranged in opposite directions, 115 the frame of the pairs connected together to be moved in opposite directions to the other frame of the pair by the movement of either frame, keys adapted to engage the step of one frame and move it until the corresponding step of the other frame of the pair engages the key when the device is locked and the amount designated by the key operated, 120 is indicated, whereby the indicating device will operate from the last indicated position without returning to zero.

10. In a device of the character described, 125 four number segments, a plurality of keys, prolongations on the respective keys, a series of pairs of frames stepped in opposite 130

directions and provided for numbers which consist of tens and units, which frames are adapted to move in opposition to one another and coöperate with the number segments, on which step projections the prolongations of the keys strike, each according to the number value, whereby a number composed of tens and units may be put to-

gether simultaneously with one key and the sum in question indicated. 10

In testimony whereof I affix my signature, in presence of two witnesses.

KARL MAIER.
